US0D1076435S

(12) **United States Design Patent** (10) Patent No.: **US D1,076,435 S**
(45) Date of Patent: ** May 27, 2025

(54) **SUITCASE**

(71) Applicant: **Weiqiang Zhou**, Vancouver (CA)

(72) Inventor: **Weiqiang Zhou**, Vancouver (CA)

(**) Term: **15 Years**

(21) Appl. No.: **35/521,971**

(22) Filed: **Jul. 26, 2024**

(80) **Hague Agreement Data**

Int. Filing Date: **Jul. 26, 2024**

Int. Reg. No.: **DM/239051**

Int. Reg. Date: **Jul. 26, 2024**

Int. Reg. Pub. Date: **Aug. 16, 2024**

(51) **LOC (15) Cl. 03-01**

(52) **U.S. Cl.**

USPC **D3/279**; D3/289

(58) **Field of Classification Search**

USPC D3/273, 276, 279, 282, 284, 294, 295,
D3/302, 905, 262, 289

CPC B25H 3/02; A45C 2005/037

See application file for complete search history.
